United States Patent Office.

JOHN STACKHOUSE, OF WEST PITTSBURG, PENNSYLVANIA.

Letters Patent No. 77,546, dated May 5, 1868.

IMPROVEMENT IN POLISHING-MACHINES.

The Schedule referred to in these Letters Patent and making part of the same.

TO ALL WHOM IT MAY CONCERN:

Be it known that I, JOHN STACKHOUSE, of West Pittsburg, in the county of Allegheny, and State of Pennsylvania, have invented a new and improved Polishing-Machine; and I do hereby declare that the following is a full, clear, and exact description thereof, which will enable those skilled in the art to make and use the same, reference being had to the accompanying drawings, forming part of this specification.

This invention relates to a new and improved machine for polishing steel rolls, and for polishing rolls, bars, and rods of other metals, and of a round form; and the invention consists in providing revolving cylinders, and also guides, between which the article to be polished is passed, as will be hereinafter more fully described.

Figure 1 represents an end elevation of the machine, showing the position of the revolving and polishing-cylinders; representing also the article to be polished, in red color.

Figure 2 is a side elevation, showing the cylinders, and the shafts to which they are attached.

Figure 3 is a vertical section through the line $x x$, showing the gearing by which the cylinders are driven. Similar letters of reference indicate corresponding parts.

This machine is supported by a suitable frame, which is attached to a platform.

The frame may be made of either wood or metal, and of convenient form.

A A' represent the frame or head-blocks, which support the cylinders.

B is the platform.

The frame consists mainly of two head-blocks for the support of the cylinders, and pillow-block for the support of the shafts and gearing.

C C' represent the cylinders.

D D' are the shafts, which are attached to the cylinders.

E represents the driving-gear wheel.

F F' are the driving-pinion, on the shafts D D'.

G G' represent the pillow-blocks, which support the back ends of the shafts and the gearing.

H represents a guide, at the front end of the machine, where the article to be polished is introduced.

J J' represent the outer journals of the cylinder.

Upon each side of the frame or head-blocks A A', there are guides I I, which extend inward under the cylinders, and approach each other near enough to be guides upon each side of the roll, so as to keep it in place, and parallel with the cylinders, while it is in contact with them and being polished.

The outer edge of one of these guides is seen in the drawing.

The shafts D D' are coupled to the cylinders, as seen in the drawing.

K K' represent the back journals of the cylinders, and L L' the couplings.

The article to be polished is passed in between the cylinders endwise at H, and is carried through between the cylinders, being trued and polished as it is revolved by them.

The roll or article to be polished is seen in red between the cylinders in fig. 1.

After passing through the machine, it is delivered on to a grooved horizontal plate, which lies between the shafts D D', and is marked m.

The journals of the upper cylinder are secured in boxes, which rest upon spiral springs, seen at n n, in the front end of the machine; similar springs being under the boxes at the other end.

o represents press-screws, which pass through the caps of the head-blocks, and bear upon the upper box, holding the cylinder C down to its work with a force which resists the tension of the springs, more or less, as may be desired.

If the springs are sufficient to bear up the weight of the cylinder, the pressure on the article to be polished may be as nicely adjusted by the screws as may be desired.

The power to revolve the cylinders is applied to the shaft of the driving-wheel, which is marked P.

R is a crank on that shaft, by which the machine may be operated by hand, if desired.

This machine is designed for giving a cold polish to all kinds of round metallic rods, rolls, or bars, from the diameter of a half inch to five inches, as may be desired; but I do not confine myself, in the use of the machine, exclusively to cold metallic rolls, rods, bars, or other articles.

Having thus described my invention, I claim as new, and desire to secure by Letters Patent—

1. The guide H for introducing the metal to be polished in a line parallel to the axial lines of the rollers C C', the guides I I for holding said metal longitudinally between said rollers, and the guide m for receiving the polished metal in the line of its passage from between the rolls, as herein described, for the purpose specified.
2. The guides H, I, and m, in combination with the polishing-rolls C C' and head-blocks A A', substantially as described, for the purpose specified.

JOHN STACKHOUSE.
